United States Patent Office

Des. 205,880
Patented Sept. 27, 1966

205,880

TIRE

Glen L. Wittenmyer, 121 Dodge Ave., Akron, Ohio

Filed Dec. 22, 1965, Ser. No. 279

Term of patent 14 years

(Cl. D90—20)

Fig. 1

FIG. 2

FIG. 1 is a perspective view of a tire showing my new design; and

FIG. 2 is a transverse cross sectional view thereof.

The dominant features of the design reside in those portions shown in full lines.

I claim:

The ornamental design for a tire, substantially as shown and described.
